UNITED STATES PATENT OFFICE.

LEON HEIMANN, OF NEW YORK, N. Y., ASSIGNOR, BY MESNE ASSIGNMENTS, TO LIVE LEATHER BELT CO., OF NEW YORK, N. Y., A CORPORATION OF NEW YORK.

PROCESS OF MAKING LEATHER MATERIAL.

1,133,957.

Specification of Letters Patent.

Patented Mar. 30, 1915.

Application filed December 7, 1912. Serial No. 735,402.

To all whom it may concern:

Be it known that I, LEON HEIMANN, a citizen of the United States, and a resident of the city, county, and State of New York, have invented certain new and useful Improvements in Processes of Making Leather Material, of which the following is a specification.

It is generally understood that leather, especially when of any substantial thickness, is non-elastic, but while yielding very slightly to tensional strain, is practically non-elastic.

The object of my invention is to produce a leather material which consists of leather so treated, handled, and manipulated, that it has all the effect of elasticity, in the uses to which it is put. Such material is particularly useful in the form of strips or bands where strength and durability are desirable, coupled with an elastic property of stretching under strain and power to return to its original length when the strain is removed. To accomplish this object, I take a piece of leather of such thickness, quality and size as may be desirable and put it through a process of crimping and steaming and sometimes softening by various fluids until the leather has become softened without any substantial weakening, and its pores opened. Then I rubberize the leather as the process is called which consists briefly in coating the inner side of the leather with a rubber-like fluid which penetrates the pores of the leather to a certain extent and solidifies. This rubberizing is done while the leather is stretched and still soft, with its pores open and its crimps or corrugations nearly or fully flattened out. Finally the stretching strain is removed so that the material contracts lengthwise as the rubber sets.

In applying this leather material to practical use, I will take the case of a belt strip which may be formed in a continuous row to be cut up afterward to the desired lengths. I have selected this simply for purposes of illustration, as it is to be understood that my improved leather material is capable of application to a great many purposes, and is not intended to be confined to belts.

In the accompanying drawing, I have shown two ways of using this material for belts for men or women.

Figure 1 is a perspective view of a belt made of my improved leather material. Fig.

2 is an enlarged front elevation of a piece of said belt, and Fig. 3 is a rear elevation thereof. Fig. 4 is a section on the line 4—4 of Fig. 3, and Fig. 5 a section on the line 5—5 of Fig. 2. Fig. 6 is an enlarged rear elevation of a portion of a belt made in almost but not quite the same manner, being a modification yet to be described. Fig. 7 is a section on line 7—7 of Fig. 6.

Same letters indicate different parts in the different figures.

A represents the piece of my improved leather material which forms the face, and sometimes also the back of the belt.

B is a strip of sheet rubber elastic webbing or other elastic material which forms a body around which said leather material is wrapped or folded.

C is the separate backing piece which may be used or not as preferred, and may be of thin leather, linen or other suitable material as desired.

The difference between the construction shown in Figs. 2 and 3 and that illustrated in Fig. 6, is that two pieces of my improved material are illustrated in the first two views, the edges of the rear piece C lapping the turned-over edges of the front piece A; whereas in Fig. 6 a single wider strip is passed around the body or core B and its edges overlapped with each other as shown. Fig. 6, however, shows the piece of belt under tension so that the crimps have disappeared.

In the process of making my improved material, the sheet or strip A is first crimped transversely of its length by any suitable means forming no part of this invention, and if there is a separate strip C that is similarly treated, but it is treated separately from the strip A and the parts connected later as above set forth. In the drawings the crimps are illustrated as extending straight across the strip, but this is not necessary so long as their general direction is transverse to its length. The piece of material is then put under tension to stretch it longitudinally slightly, whereby the crimps are caused to nearly or fully disappear and the pores in the leather are opened. I then apply a rubberizing agent, which may be of any suitable character and applied in any suitable manner forming no part of this invention; but the fact that the pores are opened at this time permits

the entrance of the agent thereinto. By preference this agent is applied while it is hot and fluid, and also while the material A is heated if desired; and the application of 5 the agent may be accompanied by pressure. Next I remove the tension from the material and allow it to contract to its former crimped condition, either fully or partly; and in this condition I permit the rubber- 10 izing agent to set. In other words, the tension is removed before the rubberizing agent has set and yet after it has entered the pores; and if pressure is employed, I prefer to apply it before the agent has set and while 15 it is still in a plastic or sticky condition so that it may be to an extent forced into the pores.

The means of applying this leather material to a body strip or core member B are 20 not essential to the present invention. If the material be employed in the manufacture of a belt for personal wear, it may be placed around and secured upon the core in any suitable manner. But if the finished 25 article is to be stretched, it is obvious that the core B must itself have some elasticity and strength.

A variety of ornamental effects can be

secured in this way by action upon the softened leather during the process of treatment, and by variations in the crimping, an effect resembling alligator skin or some other hide can be produced as shown in Fig. 2 of the drawing; the crimp lines being either regular or irregular as desired. 30 35

I claim:

1. The herein described process for manufacturing leather material, the same consisting in crimping a strip of leather transversely to its length, putting it under longitudinal tension, applying a rubberizing agent, removing the tension, and permitting said agent to set. 40

2. The herein described process for manufacturing leather material, the same consisting in crimping a strip of leather transversely to its length, putting it under longitudinal tension, applying a rubberizing agent, applying pressure to force agent into the pores of the leather, removing the tension from the latter, and permitting the agent to set. 45 50

LEON HEIMANN.
